UNITED STATES PATENT OFFICE.

JOHN H. MALLON, OF FRANCESVILLE, INDIANA.

THERMOSTAT.

SPECIFICATION forming part of Letters Patent No. 405,579, dated June 18, 1889.

Application filed January 12, 1889. Serial No. 296,210. (No model.)

To all whom it may concern:

Be it known that I, JOHN H. MALLON, of Francesville, county of Pulaski, and State of Indiana, have invented certain new and useful Improvements in Thermometrical Gas-Regulators; and I do hereby declare that the following is a full, clear, and exact description thereof, reference being had to the accompanying drawings, in which like letters refer to like parts.

My invention relates to the construction of devices for regulating the supply of gas, and I accomplish this by means of the contraction and expansion of a fluid or liquid through the increase or decrease of the temperature thereof, which will be understood from the following description.

In the drawings, Figure 1 is a longitudinal section of my device, one side of the case being removed. Fig. 2 is a detail view of a part of the device, showing the plunger elevated by the expansion of the fluid. Fig. 3 is a modification of a top of the tank and nipple. Fig. 4 is a rear view of a modification of the device to which the valve is connected. Fig. 5 is an end view of the same.

In detail, *c* is an outer case inclosing a tank *t*, made in bottle shape, with a neck, as shown. This is intended to hold the fluid or liquid *f*. The top of this tank is closed by a rubber nipple *n*, having a flanged rim, which rests upon a shoulder formed about the neck of the tank *t*.

p' is a pipe through which the plunger *p* moves. The lower end of this pipe has its bore enlarged, forming a recess *r* to admit the neck of the bottle and its covering, (the nipple,) and this recess is made larger than the neck of the bottle, in order to permit the nipple, when extended by the expansion of the fluid, to rise above the top of the tank *t*, as shown in Fig. 2. The upper end of this pipe *p'* is shouldered and fits into the movable head *h*, which is located in the case *c* about one-fourth of the distance below the top. Upon this head rests the flanged sleeve *s*, which is threaded at the top to receive a jam-nut *n'*, and when this nut is turned so as to press against the under side of the cap the sleeve is carried down with it, and also the head *h*, forcing the pipe *p'* more closely

against the flange of the nipple *n*, holding it securely in place about the shouldered neck of the tank *t*. By means of this device the regulator may be set so that it will require a certain degree of temperature in the fluid before its expansion will cause the plunger to rise, generally 70° or 80° Fahrenheit. The upper part of the plunger-rod is shouldered to receive a coiled spring *sp*, which works against the under side of the top of the case, the end of the plunger passing into such top.

w is a wire which is made with a hook at either end, or at both, as shown in Fig. 1, for the purpose of connecting the plunger with the valve to be operated upon. Ordinarily only the lower hook is intended to be used; but in some cases it may be desirable to connect the valve at the upper end of such wire, and then it is extended through the upper part of the case, as shown in Figs. 1 and 2.

In Fig. 2 the spring is shown compressed. The fluid having expanded has forced the nipple upward, carrying with it the plunger *p*, and the wire *w*, being fixed in the plunger-rod, is carried up with it, so that whatever is attached to either hook of the wire will be operated upon by the expansion of the fluid. When the fluid contracts, the force of the spring *sp* operates to throw the plunger down in the position shown in Fig. 1.

In Fig. 3 is shown a modification of the shape of the nipple. In order to give greater throw to the plunger the nipple may be made in this shape and the plunger extended down into the recess formed by the bend in the nipple; but its operation is precisely the same as the form shown in Figs. 1 and 2.

If desired to hang the device upon the wall, the valve may be operated by means of a pulley and cord, instead of a wire passing through the plunger-rod, and in such case a convenient method of construction is shown in Figs. 4 and 5.

r' is a roller journaled in the sides of the case. *br* is a bracket fixed to the top of the plunger. *k* are knobs or locking-screws to hold the roller in proper relative position. *c'* is a cord wound about the roller, extending below and connected with the device it is intended to control. As the flange expands it forces up the nipple, carrying with it the

plunger, and as the plunger rises it carries with it the bracket *br* and the roller *r'*, controlling the cord *c'* and operating the valve connected below.

- 5 In Fig. 4 the dotted lines show the position of the knobs *k* when the roller has made about a quarter-revolution; but in this form of the device the limit of vertical movement is about equal to the radius of the roller *r'*.
- 10 The form of the device shown in Figs. 1, 2, and 3 is generally preferable for controlling the operation of the valve; but in some situations the roller and cord connections shown in Figs. 4 and 5 may be better. It will be seen, therefore, that my device consists, practically, of a tank for holding the liquid, having a rubber cap upon which the plunger normally rests, and the expansion of the liquid serves to force the plunger upward and operate the valve connected to such plunger by means of wires or other similar devices, and when the temperature of the fluid falls the plunger will be forced downward by the spring and the valve will be operated in an opposite direction. If the device is for natural gas, it should be set within a convenient distance of the fire, so that as the heat of the fire increases it will raise the liquid to a corresponding degree of temperature, and the rising temperature operating the plunger so as to partially close the valve, it regulates the supply of gas to the fire, and as the temperature decreases and that of the fluid with it the necessary consequence would be that the plunger will fall and open the valve, thereby supplying more gas to the fire, and thus automatically controlling and making an even temperature throughout the room.

What I claim as my invention, and desire 40 to secure by Letters Patent, is the following, to wit:

1. In a thermometrical gas-regulator, an outer case, a vessel for holding the expandible liquid inclosed therein, an elastic nipple covering the mouth of such vessel and provided with a flange which rests upon a shoulder formed upon the neck of the vessel, a pipe having an opening to receive the mouth of such vessel, the lower end thereof abutting against the flanges of the nipple, the upper 45 end of such pipe held in position by a head movable in the outer case, an adjustable sleeve above such head inclosed in the upper part of such case for adjusting and securing such head in position, a plunger moving in said pipe 50 shouldered above to receive a coiled spring for creating a downward pressure upon such plunger, and a rod connected therewith for attachment to the mechanism to be operated upon, all combined substantially as shown 55 and described.

2. In a thermometrical gas-regulator, an outer case *c*, the vessel *t*, inclosed therein, the elastic nipple *n*, closing the mouth of such vessel, the adjustable pipe *p'*, for holding such 60 nipple in position, the spring-plunger *p*, moving in such pipe, the wire *w*, connected to such plunger and operated thereby, provided with a hook at one or both ends for connecting to the mechanism to be operated upon, and the adjusting-sleeve *s*, threaded to receive the nut *n*, held in place between the top of the case and the movable head *h*, all combined substantially as shown and described.

In witness whereof I have hereunto set my 75 hand this 11th day of December, 1888.

JOHN H. MALLON.
